WITNESS:

UNITED STATES PATENT OFFICE.

ANNA L. BENOIST, OF ST. LOUIS, MISSOURI.

PAN LIFTER.

Application filed March 27, 1922. Serial No. 547,286.

To all whom it may concern:

Be it known that I, ANNA L. BENOIST, a citizen of the United States, residing at St. Louis and State of Missouri, have invented 5 new and useful Improvements in Pan Lifters, of which the following is a specification.

This invention relates to a pan lifting device, and the object is to provide means 10 for lifting pans of various shapes and sizes, and withdrawing them from an oven.

A further object is to provide a plurality of pan engaging devices and mounting means therefor, comprising a pair of handle 15 members and means for maintaining the handle members in parallel relation, so far as adjacent edge portions are concerned, and permitting the handle members to swing with reference to each other, so that rec- 20 tangular and round pans may be handled with equal facility.

A still further object is to provide a plurality of frame members deflected to form portions directly engaging the flange of the 25 pan to be lifted, and handle members comprising bars connected by rings or links, and in such manner that the frame members may be swung to the position required for effecting the purpose specified.

With the foregoing and other objects in 30 view, the invention consists in the novel construction and arrangement of elements described and claimed, it being understood that modifications may be made within the scope 35 of the claim without departing from the spirit of the invention.

In the drawings, Figure 1 is a perspective view of the device; Figure 2 is a bottom plan view; Figure 3 is a detail view showing the manner of connecting the frame 40 with the handle.

A plurality of bars 10 and 12 provide means for mounting the frame element referred to below, and are extended to a sufficient length to provide handles by means of which the articles to be lifted may be manipulated in the manner described.

The frame members 17 may be approximately rectangular in configuration, but in

any event are provided respectively with 50 curved and offset portions designated 15 and 16. These members are designed to directly engage the pan or other article, and are slightly curved in order to conform approximately with a segment of a round or circular pan.

Each frame may be further provided with an offset at the point where the side members of the frame enters the members 10 and 12, as the case may be. These elements last 60 named are apertured, and the offset bears against the edge of element 10 or 12, in order to provide suitable support. The inner end of the side elements of the frame is bent over on the inner edge of the member 10 or 12 65 through which it passes, thereby establishing a rigid connection in a very simple manner.

The members or handles 10 and 12 are so connected that they have swinging relation, 70 by providing ring or link members 20 and 21, these elements passing through apertures, such as 22, oppositely located in elements 10 and 12.

The arrangement specified permits the 75 frame members and the handle to have free movement, and the inner edges of handles are nevertheless maintained in parallel relation. As a result a circular pan may be lifted with the same facility and with the same degree 80 of certainty, as a rectangular pan. Moreover, within the limits of the device, the size of the pan is not material.

What is claimed is:

In a device of the class described, a plurality of handles, pan engaging devices connected with the handles, and elongated links connecting the handles, loosely mounted in each handle, and permitting the pan engaging devices to separate slightly and to swing 90 outwardly while the longitudinal axes of the handles maintain parallel relation, said pan engaging devices constituting frames formed with ends each offset on opposite sides of the respective handles.

In testimony whereof I affix my signature.

ANNA L. BENOIST.
